UNITED STATES PATENT OFFICE.

WILLIAM D. HUDSPETH AND CHARLES C. HARTZOG, OF MONROE, LOUISIANA; PEECY SANDEL, EXECUTOR OF SAID CHARLES C. HARTZOG, DECEASED, ASSIGNOR TO SAID HUDSPETH.

BURGLAR-ALARM.

1,968,342.

Specification of Letters Patent.

Patented July 22, 1913.

Application filed June 19, 1912. Serial No. 704,636.

To all whom it may concern:

Be it known that we, WILLIAM D. HUDSPETH and CHARLES C. HARTZOG, citizens of the United States, residing at Monroe, in the parish of Ouachita and State of Louisiana, have invented new and useful Improvements in Burglar-Alarms, of which the following is a specification.

This invention relates to burglar alarms, 10 the object of the invention being to provide a simple, reliable and effective device for audibly indicating when a window sash or door has been opened, the device being applicable to the ordinary sash arrangement 15 used in windows, and being applied easily by any unskilled person.

A further object of the invention is to provide means whereby during the day time 20 the operative parts of the alarm may be thrown out of operative relation to each other, so that the sashes may be raised and lowered, without interfering with the alarm mechanism.

With the above and other objects in view, 25 the invention consists in the construction, combination and arrangement of parts, as will be hereinafter more fully described, illustrated in the accompanying drawings, and pointed out in the claims hereunto appended.

In the drawings: Figure 1 is a vertical cross section through the meeting rails of a pair of sashes, showing the alarm applied thereto. Fig. 2 is a view in elevation of the 35 same. Fig. 3 is an enlarged detail view, showing the main parts of the alarm tripping mechanism in their relation to each other. Fig. 4 is a detail view of the hinged and folding lug.

Referring to the drawings, 1 designates the bottom rail of the upper sash, and 2 the top rail of the lower sash.

The burglar alarm embodies a base plate 3, provided with any suitable number of 45 holes 4 adapted to receive screws or like fasteners, whereby said plate is secured to the inner face of the meeting rail 2 of the lower sash, in a manner illustrated in Figs. 1 and 2. Extending outwardly from the 50 base plate 3 is the post 4 of a rotary bell 5, containing suitable mechanism, such as a hammer and actuating mechanism therefor, whereby when the bell is released and allowed to be revolved by the usual spring, the 55 bell is sounded. Extending upwardly from

the bell is a plunger trip or rod 6 which, when pressed downward or toward the center of the bell, releases the mechanism which causes the bell to be sounded. Extending outwardly from the top of the plate 3 is a 60 bracket 7 having an upwardly extending terminal portion 8, upon which is pivotally mounted, at 9, a sleeve 10, through which passes a lever 11, the same being threaded to receive one or more nuts 12 and 13, by 65 means of which the lever 11 may be adjusted in the direction of its length, for a purpose which will hereinafter appear. The bracket 7 is also provided with a guide opening 14, through which the plunger trip 6 is arranged 70 to slide, as shown in Fig. 1, said trip being normally upheld by means of a coiled spring 15 which extends around the plunger trip 6 and is interposed between the bracket 7 and a head or shoulder 16 at the upper end of 75 the plunger rod. The lever 11 rests upon the head 16 of the plunger, so that when said lever is depressed, the plunger is correspondingly depressed, thereby releasing the mechanism which actuates the bell 5. Connected 80 to the bottom rail 1 of the upper sash is an outwardly projecting lug 17 which cooperates with the extremity of the lever 11, for depressing the lever, either when the upper or lower sash is opened.

In the preferred embodiment of this invention, the lug 17 is hinged at 18 to a bracket or attaching plate 19 secured to the rail 1 of the upper sash, as by this arrangement the lug 17 may be folded back against 85 the sash or into a recess in the face of the sash, so as to be out of the path of the lever 11, thus enabling the device to be thrown out of use in the day time. Furthermore, the lever 11 may be moved outward in the 90 direction of its length, so as to carry the inner end thereof out of the path of movement of the lug 17, even when it is in a projecting position, as shown in Fig. 1. Either of the adjustments referred to will 95 throw the device out of operation in the day time, when it is not needed, and either one of said elements will enable the device to be thrown into operation, when desired. If desired, a set screw 20 may be used for fixing the adjustment of the lever 11 in the sleeve 10.

What is claimed is:

1. In a burglar alarm, a rotary bell, a plate on which said bell is supported, a 110

- bracket on said plate, a lever fulcrumed on said bracket, a plunger arranged to be operated by said lever and adapted to trip the bell actuating mechanism, and a lug with 5 which the lever is adapted to come into contact upon movement of the window sash or door in connection with which the alarm is used, said lever being adjustable into and out of the path of said lug.
- 10 2. In a burglar alarm, a rotary bell, a plate on which said bell is supported, a bracket on said plate, a lever fulcrumed on said bracket, means for adjusting said lever in the direction of its length, a plunger ar-

ranged to be operated by said lever and 15 adapted to trip the bell actuating mechanism, and a lug with which the lever is adapted to come into contact upon movement of the sash in connection with which the alarm is used. 20

In testimony whereof we affix our signatures in presence of two witnesses.

WILLIAM D. HUDSPETH.
CHARLES C. HARTZOGUE.
